Inventor,

James A. Porter

UNITED STATES PATENT OFFICE.

JAMES A. PORTER, OF CRAWFORDSVILLE, INDIANA, ASSIGNOR OF ONE-HALF
TO WILLIAM B. GRIFFITH, OF CRAWFORDSVILLE, INDIANA.

CHIMNEY-BACK.

No. 853,897.

Specification of Letters Patent.

Patented May 14, 1907.

Application filed April 7, 1906. Serial No. 310,550.

To all whom it may concern:

Be it known that I, JAMES A. PORTER, a citizen of the United States, residing at Crawfordsville, in the county of Montgomery and State of Indiana, have invented certain new and useful Improvements in Chimney-Backs, of which the following is a specification.

My invention relates more particularly to improvements in integral, metallic chimney backs for roofs and to this end my invention consists in the peculiar form, combination and arrangement of the integral parts as will be more fully set forth hereinafter.

15 A further objective sought and attained in my invention is the production of an integral, metallic chimney back for roofs which effectually prevents rain and snow from entering between the chimney and the roof and 20 which causes debris, dirt, snow etc, to gravitate away from it and away from the chimney. This attainment avoids the usual accumulation of debris, dirt, snow etc, over the chimney back and between the chimney and 25 the roof which ordinarily hastens the corrosion and destruction of the metallic back.

30 My main objective is to produce an efficient, durable and profitable article of manufacture of integral sheet metal of any suitable nature, for instance such as tin, zinc, copper etc, of more economy in cost and service than has been done heretofore.

35 In the accompanying drawings, forming a part of this specification wherein like letters and numerals of reference indicate corresponding parts throughout the several views: Figure 1 is a top plan of my invention entire. Fig. 2 is an elevation of my invention entire taken from its chimney side. Fig. 3 is a vertical section on the line *m, n*, Fig. 1. Fig. 4 is a top plan of a chimney and roof with my invention properly applied.

40 In the construction of my invention an integral sheet metal strip of any suitable material is bent into such form as fully attains my object. A represents a chimney of common form and use. B is a section of a roof. C refers to the roof section of my invention, C' to the chimney portion, and C² C³ and C⁴ C⁵ to its double dividing slopes of the bridge part 45 D D' indicate points whereabout the chimney corners touch the portion C'.

The double inclined slopes C² C³ and C⁴ C⁵ form an angular bridge part between the in-

clined roof section C and the vertical chimney portion C' of my invention which divides and delivers the water fall beyond and away from the chimney corners and prevents any leakage at the upper roof side of the chimney. The double inclined slopes C² C³ and C⁴ C⁵ also 55 gravitate debris, dirt, etc, from the upper roof side of the chimney where it most usually accumulates and discharges it beyond and away from the chimney corners. This peculiar provision of an integral, angular bridge 60 part efficiently braces and strengthens all the integral parts of my invention.

E E' refer to delivery points which are below and beyond the upper corners of the chimney.

70 It will be observed that my invention is applied to the angle between the chimney A and the upper part of the roof B and that its roof section C is underneath the roofing of shingles, slate or metal, but which has been 75 shown of shingles for an illustrative purpose only. In the above construction an integral metallic chimney back for roofs is produced without seams in the bends which makes a 80 desirable article of manufacture with or without stamping machinery.

It will readily be seen that sizes corresponding with most chimneys in common use and with the usual inclines of roofs may be made as a commercial article. My invention may 85 be hand made of several soldered pieces without departing from its spirit and scope but its manufacture of an integral strip of sheet metal is more preferable.

90 I am aware of similar devices in which several parts have been united and applied about the chimney heretofore and I do not claim any of them but my metallic chimney back which has double inclined slopes and an angular bridge part made in the manner and for 95 the purposes above set forth, is both new and useful, and what I claim as my invention and desire to secure by Letters Patent, is,—

1. An integral metallic chimney back for 100 roofs, the same comprising an inclined roof section, a vertical chimney portion, and an angular bridge part having a pair of double slopes inclined transversely from and laterally with the walls of the roof section and the chimney portion inwardly together for the 105 purposes set forth, substantially as specified.

2. In an integral metallic chimney back 110 for roofs, the combination with the chimney

and the roof of an integral metallic chimney back having an inclined roof section, a vertical chimney portion, and an angular bridge part comprising a pair of double slopes inclined transversely from and laterally with the walls of the roof section and the chimney portion inwardly together for the purposes of

structural rigidity and for gravitating rain, debris, etc. as set forth, substantially as specified.

JAMES A. PORTER.
